OTHER PUBLICATIONS

Star handbag—published approximately in 2008/2009—Admitted prior art.

Primary Examiner — Karen S Acker

(74) Attorney, Agent, or Firm — Fross Zelnick Lehrman & Sissu, P.C.; Lawrence E. Apolzon, Esq.

(57) CLAIM

The ornamental design for a fabric, as shown and described.

DESCRIPTION

The sole FIGURE is a plan view of a fabric, showing my new design.

The broken lines surrounding the FIGURE depict the boundaries of the claim and form no part thereof.

1 Claim, 1 Drawing Sheet(56)
